(57) **CLAIM**

The ornamental design for a folding chair having quilted fabric, as shown and described.

DESCRIPTION

FIG. 1 is a left front perspective view of a folding chair having quilted fabric in an open configuration;

FIG. 2 is a right front perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The short even dashed lines shown on the seat and backrest are understood to represent stitching.
